pany, Milwaukee, Wis., a corporation of Wis-
consin

Application August 31, 1942, Serial No. 108,086

Term of patent 14 years

To all whom it may concern:

Be it known that we, John C. Cleaver and Jules
Verne Resek, citizens of the United States, resid-
ing at Whitefish Bay, County of Milwaukee, State
of Wisconsin, have invented a new, original, and
ornamental Design for a Combination Boiler and
Sterilizer or the like, of which the following is a
specification, reference being had to the accom-
panying drawing, forming a part thereof.

Figure 1 is a front perspective view of a com-
bination boiler and sterilizer showing our new
design.

Figure 2 is a rear perspective view thereof.
The dominant features of the invention reside
in the portions shown in full lines.

We claim—

The ornamental design for a combination
boiler and sterilizer or the like, as shown, and
described.
